UNITED STATES PATENT OFFICE.

LEWIS H. JOHNSON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,212,495.

Specification of Letters Patent. Patented Jan. 16, 1917.

Application filed July 24, 1916. Serial No. 111,010.

To all whom it may concern:

Be it known that I, LEWIS H. JOHNSON, a citizen of the United States, residing at Bloomfield, in the county of Essex and 5 State of New Jersey, have invented certain new and useful Improvements in Telephone-Exchange Systems, of which the following is a full, clear, concise, and exact description.

This invention relates to telephone exchange systems and more particularly to such systems which employ automatic ringing for signaling purposes and which are provided with trunk lines extending to 15 private branch exchanges, chief operators' desks and like positions.

As applied to ordinary subscribers' lines, automatic or keyless ringing has proven very satisfactory, but when employed in signaling between different operators' positions, for instance, between central office and private branch exchanges or between an answering operator and a chief operator's or wire chief's desk, the method of 25 signaling by means of automatic ringing has been found to possess an inherent defect which manifests itself in the form of an objectionable click in the ears of the signaled and answering operator. This objectionable click is due to the inclusion of 30 the answering operator's receiver directly in the circuit upon which ringing current is being impressed, when the listening key is actuated in response to a call. The ringing current is cut off immediately upon the 35 inclusion of the receiver in circuit therewith, but not before it has given the operator the disagreeable click, which is due to the action of the central office mechanism 40 in transferring the trunk leads from the source of ringing or alternating current to the source of direct current upon the actuation of the listening key. This objectionable click is not met with in signaling an ordinary subscriber, for the reason that the 45 mechanism at the central office operates to disconnect ringing current from the line and substitute talking current therefor in the interval between the time the subscriber 50 removes the receiver from the switchhook and the time it is placed to the ear of the subscriber.

It is very desirable that this objectionable and disagreeable feature be eliminated,

and this invention has that purpose for its 55 object.

In accordance with this invention, when an operator answers a call by actuating a listening key, a quick operating and slow releasing relay is operated to disable the 60 answering operator's receiver, and maintain this receiver disabled until after the ringing current has been cut off and talking current substituted therefor, and the operator's 65 telephone set connected with the trunk circuit.

This invention is illustrated in the accompanying drawing in which all apparatus is shown in its normal and unactuated condition.

There is shown in the drawing a telephone exchange system containing one embodiment of this invention, and comprising a cord circuit A located at one section C of a switchboard, and a trunk circuit B extending from this section C to a desk operator's position D, at which there is a signaling device, a listening key and an operator's telephone set. It is believed that this invention will be fully understood from a 80 description of the operation of the system shown in the drawing, and it will be so described.

The operator at section C, desiring to signal the desk operator D, inserts a plug 85 5 into a jack 6, whereupon lamp 7 will be lighted and relay 8 operated. The operation of relay 8 causes the actuation of a ringing relay 9 over a circuit from battery through resistance 10, winding of relay 9, 90 normal contact of relay 11, contact of trip relay 12 and the closed contact of relay 8 to ground. The operation of ringing relay 9 connects a source of ringing current 15 to the trunk circuit B, causing the operation 95 of relay 16 over a circuit from the source of ringing current 15 through the winding of trip relay 12, lower alternate contact of ringing relay 9, ring contacts of plug 5 and jack 6, condenser 17, right-hand winding of 100 relay 16, tip contacts of jack 6 and plug 5 and upper alternate contact of ringing relay 9 to ground. The operating winding of relay 16 is of high impedance, so that trip relay 12 is not actuated when in circuit with relay 16. Upon the actuation of relay 16, it is locked up over a circuit from battery through the left-hand winding and

contact thereof and the normally closed contact of listening key 18 to ground. The lamp 19 is lighted upon the actuation of relay 16 to furnish a signal to the desk operator, and remains lighted until the desk operator actuates the listening key 18. The ringing current also remains connected to the trunk circuit until the actuation of the listening key 18 by the desk operator.

- 16 The desk operator, upon observing the lighted condition of lamp 19, actuates listening key 18 which opens the locking circuit of relay 16 and the circuit of lamp 19, thereby extinguishing the lamp. The actuation of listening key 18 causes the operation of a quick operating and slow releasing relay 25 over a circuit from battery through the winding of relay 25, lower normal contact of relay 26, contact of relay 27, and contact 28 of key 18 to ground. Relay 25, in operating, short-circuits the desk operator's receiver 29, and maintains this short circuit until after the ringing current is tripped and the operator's telephone set is connected 25 with the trunk circuit, as will hereinafter more fully appear.

By the actuation of the listening key 18, a slow operating relay 27 of low impedance is included in circuit with the source of ringing current 15, so that trip relay 12 and relay 27 operate. Relay 12, in operating, opens its contact, removing a short circuit from and permitting relay 11 to operate. Relay 11 is thereupon locked up over a circuit from battery through resistance 10, alternate contact and winding of relay 11 and contact of relay 8 to ground. The operation of relay 11 also establishes a short circuit for the ringing relay 9, which thereupon releases, removing ringing current from the trunk circuit. The operation of relay 27 opens its contact, thereby removing a short circuit from and permitting the energization of relay 26 over the circuit including relay 25 and contact 28 of key 18. When it operates, relay 26 locks up over a circuit from battery, through its alternate contact and winding and contact 28 of listening key 18 to ground and establishes a short circuit for relay 25 which is thereupon deprived of current. The operation of relay 26 also closes contact 31 in the talking circuit thereby connecting the operator's telephone set with the trunk circuit, but, since relay 25 is slow in releasing, contact 31 is closed and supervisory relay 30 operates before the short circuit is removed from the desk operator's receiver 29, thereby preventing any objectionable and disagreeable clicks in the receiver. The operating circuit for supervisory relay 30 may be traced from battery through a winding 32 of repeating coil 33, winding of supervisory relay 30, lower normal contact of ringing relay 9, ring contacts 65 of plug 5 and jack 6, contact 34 of listening

key 18, contact 31 of relay 26, impedance coil 35, contact 36 of listening key 18, tip contacts of jack 6 and plug 5, normal upper contact of ringing relay 9 and winding 37 of the repeating coil 33 to ground. The operation of supervisory relay 30 places the resistance 10 in parallel with the lamp 7 which is thereby effaced, indicating to the operator at section or position C that the desk operator D has answered. 75

What is claimed is:—

1. The combination with two telephone switchboards connected together by a pair of conductors, means at one of said boards adapted to complete a circuit for said conductors and to apply ringing current over said conductors to said other board, a signaling device operated thereby, a listening key, an operator's receiver, a relay operated upon the actuation of the listening key to short-circuit the receiver, means for disconnecting ringing current from the circuit, and a relay operating thereupon to include the operator's telephone set in the circuit, the operation of said second mentioned relay permitting the first mentioned relay to release and remove the short circuit from the receiver. 85

2. A telephone exchange system comprising a pair of conductors joining two switchboards, a source of ringing current at one board, means thereat for impressing current from said source over said conductors, a signaling device at the other board operated thereby, an operator's telephone set thereat, 95 a listening key, a relay operated upon the actuation of the listening key to establish a short circuit for the receiver of the operator's set, means rendered effective by the actuation of the listening key to disconnect the ringing current from the circuit, and means operating thereupon to include the telephone set in circuit with said conductors and thereafter remove the short circuit from the receiver. 100

3. A telephone exchange system comprising a trunk circuit extending from one telephone switchboard to a second board, means at one of said boards for applying ringing current over said trunk to the other board, 115 a switch actuated by the operator at that board for disconnecting the ringing current from the trunk, an operator's telephone set, means operated upon the actuation of the switch to short-circuit the receiver of the 120 operator's telephone set, and means operating upon the removal of the ringing current to connect the operator's telephone set to the trunk circuit and thereafter cause the removal of the short circuit from the receiver. 125

4. A telephone exchange system comprising a trunk circuit extending from one telephone switchboard to a second board, means at one of said boards for applying ringing 130

current over said trunk to the other board, a switch actuated by the operator at that board for disconnecting the ringing current from the trunk, an operator's telephone set, a relay operated by the actuation of the switch to short-circuit the receiver of the operator's telephone set, and means operating upon the removal of the ringing current to connect the operator's telephone set to the trunk circuit and thereafter cause the removal of the short circuit from the receiver.

actuation of the switch to short-circuit the receiver of the operator's telephone set, and 55 a relay operating upon the removal of the ringing current to connect the operator's telephone set to the trunk circuit and to divert current from the slow release relay.

8. A telephone exchange system comprising a trunk circuit extending from one telephone switchboard to a second board, means at one of said boards for applying ringing current over said trunk to the other board, a switch actuated by the operator at that board for disconnecting the ringing current from the trunk, an operator's telephone set, means operated upon the actuation of the switch to disable the receiver of the operator's telephone set, and means operating after the removal of the ringing current to connect the operator's telephone set to the trunk circuit and thereafter render the disabling means ineffective. 60 65 70

9. A telephone exchange system comprising a trunk circuit extending from one telephone switchboard to a second board, means at one of said boards for applying ringing current over said trunk to the other board, an operator's telephone set at said other board, a switch thereat actuated by the operator for connecting the operator's telephone set to the trunk and for disconnecting the ringing current from the trunk, and means for disabling the receiver of the operator's telephone set during the period in which the ringing current is being removed. 75 80 85

10. A telephone exchange system comprising a trunk circuit extending from one telephone switchboard to a second board, means at one of said boards for applying ringing current over said trunk to the other board, an operator's telephone set at said other board, an operator-controlled switching device thereat actuated for connecting the operator's telephone set to the trunk and for disconnecting the ringing current from trunk, and a relay controlled by the switching device for temporarily disabling the receiver of the operator's telephone set during the period in which ringing current is being removed. 90 95 100

In witness whereof, I hereunto subscribe
my name this 22d day of July, A. D. 1916.

LEWIS H. JOHNSON.
